UNITED STATES PATENT OFFICE

95,984

DESIGN FOR A CARPET SWEEPER SHELL

Fred W. Pullen, Grand Rapids, Mich., assignor
to Bissell Carpet Sweeper Company, Grand
Rapids, Mich.

Application September 29, 1934, Serial No. 53,434

Term of patent 14 years

To all whom it may concern:

Be it known that I, Fred W. Pullen, a citizen of the United States, residing at Grand Rapids, county of Kent, State of Michigan, have invented a new, original, and ornamental Design for Carpet Sweeper Shell, of which the following is a specification, reference being had to the accompanying drawing, forming part thereof, in which:

Fig. 1 is a perspective view of a carpet sweeper shell showing my new design,

Fig. 2 is an end view of the shell, showing the contour.

The dominant feature of my design resides in

the arrangement of the panels of the carpet sweeper shell on a substantially flat arc in which sharp angles at the juncture of the panels are eliminated, thereby producing a slightly interrupted, ornamental, streamline shell in which the identity of the panels is not lost, which gives to the carpet sweeper shell the appearance of lowness.

I claim:

The ornamental design for a carpet sweeper shell, substantially as shown and described.

FRED W. PULLEN.
